CLAIM

We claim the ornamental design for a case for mobile phone, as shown and described.

DESCRIPTION

FIG. 1 is a front view of a case for mobile phone showing our new design;

FIG. 2 is a rear view thereof;

FIG. 3 is a left side view thereof;

FIG. 4 is a right side view thereof;

FIG. 5 is a top view thereof;

FIG. 6 is a bottom view thereof;

FIG. 7 is a front, left and top perspective view thereof; and,

FIG. 8 is a rear, left and bottom perspective view thereof.

The broken lines depict portions of the case for mobile phone in which the design is embodied that form no part of the claimed design.

1 Claim, 8 Drawing Sheets(56)
